UNITED STATES PATENT OFFICE.

JOSEPH N. KORY, OF DENVER, COLORADO.

SAMPLE-CARRIER.

1,328,167.

Specification of Letters Patent. Patented Jan. 13, 1920.

Application filed March 25, 1919. Serial No. 284,952.

To all whom it may concern:

Be it known that I, JOSEPH N. KORY, a citizen of the United States, residing at Denver, in the county of Denver and State 5 of Colorado, have invented certain new and useful Improvements in Sample-Carriers, of which the following is a specification.

This invention relates to an improved sample carrier for sending samples of cotton or other similar fibrous material from 10 one place to another and the principal object of the invention is to provide a carrier so constructed that the cotton will remain flat to show the length of the staple and to 15 further so construct the carrier that the length of the staple may be easily ascertained.

Another object of the invention is to so construct this carrier that it will be suitable 20 for sending through the mail if so desired and to further so construct it that a great many may be stored in a small space but permitting these sample cases to be retained or as a permanent record of cotton sent out or 25 taken in.

Another object of the invention is to so construct this carrier that it may be easily opened when desired but to further so construct it that there will be no danger of it 30 accidentally opening while in transit and thus permitting the samples to become lost or damaged.

Another object of the invention is to so construct this sample case that it may be 35 formed either of sheet material stamped and bent to the proper shape or it may be provided with a heavier construction if so desired and formed either of cast material or of wood or other similar material.

40 This invention is illustrated in the accompanying drawings wherein:

Figure 1 is a top plan view of the improved sample carrier,

Fig. 2 is a longitudinal sectional view 45 through the carrier,

Fig. 3 is a plan view of a card which may be used in connection with this carrier,

Fig. 4 is a longitudinal sectional view 50 through a carrier showing a slightly modified construction.

This improved carrier may be formed of sheet metal or other similar material as shown in Figs. 1 and 2 or it may be formed of wood or the like as shown in Fig. 4. This 55 carrier will be provided with a body plate 1 which may be termed a backing plate and

will be provided with side flanges 2 and an end flange 3, the end flange extending inwardly and upwardly at an incline as shown in Fig. 2 and engaged by the end 60 portions 4 of the side flanges or walls 2. These flanges or walls 2 and 3 will engage the sides and end of the transparent cover plate 5 and the plate will be securely held in place when the clamping plate 6 is moved to 65 the operative position shown in Fig. 2. This clamping plate 6 fits upon the backing plate 1 and is provided with an upstanding flange or inner end portion 7 extending at an incline similar to the flange or wall 3 and engaging the cover plate 5 when the clamp is moved to the operative position and secured by fasteners 8. These fasteners 8 are in the form of screws which pass through slots 9 formed in the clamp 6 and are screwed into 70 threaded openings formed in the backing plate 1. From an inspection of Fig. 2 it will be seen that the flange 7 and the flange 3 have been extended beyond the side flanges or walls 2 so that the transparent cover will 75 be protected and not liable to become broken.

In the form shown in Fig. 4 the tray or sample carrier is shown formed of wood or cast material. In this form there is provided the backing plate 10 the side flanges 85 11 and the end flange 12, the flanges or walls 11 and 12 being provided with grooves 13 to receive the cover plate or glass 14. The wall 15 which takes the place of the securing plate or clamp 6 is pivotally mounted between the side walls or flanges 11 and when 90 swung upon the pivot 16 to the operative position will engage the plate 14 and securely hold it in position. It will be readily seen that when the securing wall 15 is swung 95 upwardly that the cover 14 will be securely held in place. It will be further seen that this wall will not be liable to swing to an inoperative position as it fits between the wall 11 and by frictional engagement therewith will be held in place.

Within the case there is placed a card 17 upon which will be marked a scale and upon this card will be placed a pad 18 of cloth or some other material to which raw cotton 105 will adhere. The sample can therefore be placed upon this pad and will adhere to it without the use of paste or other adhesive which might damage the sample. This pad will preferably be of a dark color so that the 110 cotton will show up clearly against it. If desired the pad 18 can be eliminated and the

card 17 formed of dark and rather rough paper to which the cotton staple will cling. Lines are marked across the face of the card 17 from the indicating numbers at the sides of the card and will thus be seen that the length of the staple can be readily ascertained. This pad 18 does not need to be secured upon the card 17.

When in use a sample of cotton may be placed upon the pad or card and the transparent cover plate put in place and secured. This sample case can then be sent out either as a sample of goods handled or as a sample of goods desired. When the tray is received the sample may be looked at through the cover plate and the length and variations easily obtained by means of the scale marked upon the card. If it is desired to send additional information in connection with the sample a card 19 such as shown in Fig. 3 could be placed in the tray along with the card 17 or the card may be pasted to the

back of the tray. These trays may be maintained as a permanent record of goods sent out or received as well as being used as sample carriers. 25

What is claimed is:

1. A sample tray comprising a backing plate having side flanges and a flange at one end, a transparent cover plate sitting upon the backing plate and engaged by said flanges, a scale card between the backing plate and cover plate, a carrier pad between the scale card and cover plate, and a fastener element engaging the cover plate to hold the cover plate in position. 30

2. A sample carrier comprising a tray, a cover plate for the tray of transparent material, a scale card, a pad between the card and cover plate, and means for holding the cover plate in position. 40

In testimony whereof, I affix my signature hereto.

JOSEPH N. KORY.
